DESIGN FOR A BOX

Frank McIntosh, New York, N. Y., assignor to Letheric Incorporated, New York, N. Y., a corporation of New York

Application February 19, 1941, Serial No. 99,103

Term of patent 3½ years

To all whom it may concern:

Be it known that I, Frank McIntosh, a citizen of the United States, residing at New York city, in the county of New York and State of New York, have invented a new, original, and ornamental Design for a Box, of which the following is a specification, reference being had to the accompanying drawing, forming part thereof:

Fig. 1 is a perspective view of a box showing my new design;

Fig. 2 is a perspective view displaced about 120° from that shown in Fig. 1; and
Fig. 3 is a top plan view thereof.

I claim:

The ornamental design for a box, substantially as shown.

FRANK MCINTOSH.
